UNITED STATES PATENT OFFICE.

CHRISTIAN M. OLSON, OF MINNEAPOLIS, MINNESOTA, ASSIGNOR TO WILLIAM EDWIN NELSON, OF MINNEAPOLIS, MINNESOTA.

METHOD OF MAKING STRIP SHINGLES.

No Drawing.

Application filed February 10, 1923. Serial No. 618,387.

To all whom it may concern:

Be it known that I, CHRISTIAN M. OLSON, a citizen of the United States, resident of Minneapolis, in the county of Hennepin and State of Minnesota, have invented certain new and useful Improvements in Methods of Making Strip Shingles, of which the following is a specification.

In making strip shingles it has been customary to apply to one surface of a sheet of felt a coating of asphalt, or similar material, and, while the asphalt is soft, to apply thereto a covering or layer of mineral matter, such as finely divided slate. The mineral matter is pressed into the asphalt coating and is thereby caused to adhere to the sheet.

These coated sheets are preferably formed in long strips that are rolled up and handled in the rolls. In order to form strip shingles from the prepared sheets, it has been customary to pass the sheet through a cutting machine having knives that cut through the mineral coating, and through the layers of asphalt and felt, thereby dividing the coated sheet into strip shingles of any desired size and shape. While this is the method universally employed for cutting the prepared sheets into strip shingles, such method is objectionable in that cutting through the mineral covering quickly dulls the knives, and, moreover, even when the knives are sharp, a smooth cut through the mineral coating cannot be made, as the pressure of the knives on the mineral surface will produce ragged or torn edges. This result is much more pronounced and objectionable when the knives become dull, which they quickly do, from cutting through the slate or mineral covering.

I have discovered that by cutting through the felt sheet, and into, but not through, the asphalt coating, on lines outlining the pattern or configuration desired for the shingle, the sheet will separate on said lines, the mineral covering breaking or dividing on said lines with smooth edges. I obviate or dispense with any cutting into, or through, the mineral covering, and any tearing of such covering or of the sheet, and produce strip shingles of any desired outline having smooth, unbroken edges.

In carrying out my invention I preferably employ a felt sheet having a thickness

of about sixty one-thousandths (60/1000) of an inch. To this sheet I apply a coating of asphalt having a thickness of substantially forty one-thousandths (40/1000) of an inch. To the asphalt coating I apply a mineral covering, preferably crushed slate having a thickness of about thirty-five one-thousandths (35/1000) of an inch. I then, by means of a suitable cutting press—either platen or cylinder—cut through the felt or foundation sheet and partly through the asphalt coating, but not into the mineral covering. The lines of the cuts, in the felt, outline the shingles; and when the sheets are removed, or pass through the press, the sheets will separate on the lines of the cuts, the mineral coating breaking through on such lines and producing separate strip shingles with smooth edges throughout.

It is necessary in carrying out this invention to cut through the foundation sheet of felt and into the asphalt, but it is not necessary to cut through the asphalt coating nor into the mineral covering, as the fibers of the felt being completely severed on the lines arranged to produce the outlines desired for the shingle the asphalt coating and fine mineral or slate covering, both of which are nonfibrous, will break through on the lines of the cuts through the felt or fibrous sheet.

I claim as my invention:

1. The process of making strip shingles from a sheet of fibrous material coated on one surface with an adherent material and finely divided mineral material which consists in dividing the sheet into separate strip shingles by cutting through the fibrous sheet and into but not through the coating, then separating the shingles on the lines of the cuts through the fibrous material.

2. The process of making strip shingles from a sheet of felt having on one surface a coating of asphalt and finely divided mineral material which consists in cutting through the felt material and asphalt but not through the mineral material on lines to form the shingles then breaking through the mineral material on the lines of the cuts in the felt.

In witness whereof, I have hereunto set my hand this 7th day of February, 1923.

CHRISTIAN M. OLSON.
